UNITED STATES PATENT OFFICE

2,327,895

SAND SPREADER

Justin A. Holden, Brattleboro, Vt.

Application January 22, 1942, Serial No. 427,820

1 Claim. (Cl. 275—2)

The present invention relates to new and useful improvements in sand spreaders, particularly for sanding sidewalks, although it will be understood, of course, that the device may be used for any other purpose for which it may be found adapted and desirable.

An important object of the invention is to provide, in a manner as hereinafter set forth, a sand spreader of the aforementioned character which is adapted to be expeditiously mounted for operation on a tractor or other vehicle.

Another very important object of the invention is to provide a spreader of the aforementioned character comprising novel means, including the exhaust from the tractor or other vehicle, for uniformly spreading the sand in the desired direction over a considerable area.

Still another very important object of the invention is to provide a sand spreader of the character described which embodies unique means for controlling or regulating the discharge of the sand.

Another important object of the invention is to provide a sand spreader comprising means for agitating the sand in a manner to assure a uniform flow or discharge of said sand.

Other objects of the invention are to provide a sand spreader of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a sand spreader constructed in accordance with the present invention.

Figure 2 is a view in vertical longitudinal section through the device.

Figure 3 is a fragmentary view in bottom plan.

Figure 4 is a view in horizontal section, taken substantially on the line 4—4 of Figure 1.

Figure 5 is a detail view in top plan of what may be referred to as the spreader nozzle.

Referring now to the drawings in detail, it will be seen that the embodiment of the invention which has been illustrated comprises a hopper 1 for the reception of the sand to be spread, which hopper may be of any suitable material and capacity. Also, the hopper 1 may be se-

cured for operation on the rear of various types of tractors or other combustion engine driven vehicles in any desired manner.

Depending from the bottom 2 of the hopper 1 is a discharge spout 3. Fixed on the lower end portion of the discharge spout 3, on diametrically opposite sides thereof and depending therefrom, is a pair of opposed, parallel metallic guides 4. Mounted for sliding movement toward and away from each other in the guides 4 is a pair of shutter plates 5 which regulates the discharge of sand from the spout 3. Ears or the like 6 rise from the outer end portions of the shutter plates 5. Adjusting screws 7 are threaded through the ears 6 and rotatably connected at 8 to the spout 3 for adjusting the shutter plates 5. The elements 4 to 8, inclusive, constitute a gate valve for the spout 3.

Mounted beneath the spout 3 for receiving the sand therefrom is a nozzle which is designated generally by the reference numeral 9. The nozzle 9 is of the shape shown to advantage in Figure 5 of the drawings and comprises a bottom plate 10 from the sides of which apertured ears 11 project. The ears 11 accommodate rods 12 which depend from the bottom 2 of the hopper 1 for firmly securing the nozzle 9 in position beneath the spout 3. Rising from the plate 10 is an inclined wall 13 which is substantially U-shaped in plan. Thus, the front end of the nozzle 9 is left open for the discharge of the sand. At the front or discharge end of the nozzle 9, the plate 10 terminates in an upwardly inclined flange 14 constituting a spreading lip which directs the sand upwardly. The plate 10 further includes a raised portion 15.

Extending downwardly through the hopper 1 and the spout 3 into the nozzle 9 is an exhaust gas conduit or pipe 16. The lower or discharge end of the exhaust pipe 16 is located above the raised portion 15 of the plate 10, which raised portion functions as a spreader for the exhaust gases. The pipe 16 may be connected in any suitable manner to the exhaust of the engine of the tractor or other vehicle. The opposed inner edges of the shutter plates 5 are provided with notches or recesses 17 which receive the exhaust pipe 16 when said shutter plates are closed.

Operable in the lower portion of the hopper 1 is an agitator 18. The agitator 18 is operatively connected to a shaft 19 by a belt and pulley connection 20. The shaft 19 may be driven from any suitable source of power.

It is thought that the operation of the device will be readily apparent from a consideration of

the foregoing. Briefly, with the shutter plates 5 adjusted as desired, the sand flows by gravity from the hopper 1 through the discharge spout 3 into the nozzle 9. Exhaust gases under pressure are discharged from the pipe 16 into the central portion of the nozzle 9, said exhaust gases impinging the spreader 15 and being distributed thereby. The exhaust gases discharge the sand in a blast from the nozzle 9, the construction and arrangement being such as to uniformly spread said sand over a considerable area in the desired direction. The agitator 18 prevents clogging and assures a uniform flow of the sand from the hopper 1. The shutter blades 5 may be expeditiously and accurately adjusted as desired to regulate the volume of sand leaving the hopper 1 through the medium of the screws 7. If desired, the spreader may be mounted for operation on the front end of a vehicle, instead of the rear thereof. Also, the device may be operated, in conjunction with a suitable engine, from a wheelbarrow or other hand operated carrier.

It is believed that the many advantages of a sand spreader constructed in accordance with

the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A sand spreader comprising a hopper for the reception of sand, a discharge spout depending from said hopper, a spreading nozzle mounted beneath said spout for receiving the sand therefrom, a pipe extending downwardly through the hopper and the spout into the nozzle for discharging exhaust gases into said nozzle for blasting the sand therefrom, said nozzle including a plate, a substantially U-shaped wall rising from said plate, a spreader for the exhaust gases on the plate in opposed relation to the discharge end of the pipe, and an upturned lip on the plate at the outlet of the nozzle for directing the discharging sand upwardly.

JUSTIN A. HOLDEN.
